TREATING HYDROCARBON OILS

Albert G. Peterkin, Jr., Bryn Mawr, Pa., assignor
to The Atlantic Refining Company, Philadel-
phia, Pa., a corporation of Pennsylvania

Application August 29, 1931, Serial No. 560,086

3 Claims. (Cl. 196—48)

This invention relates to a combined cracking and coking process and contemplates a process in which raw charging stock is subjected to coking and cycle condensate is subjected to cracking and distillation to form a fuel oil residue.

When cracked residues, such as the residues withdrawn from pressure cracking stills, are subjected to coking there is a tendency toward the formation of permanent gases instead of gasoline constituents and furthermore the gas oil product formed is highly refractory and difficult to crack. Therefore, in accordance with my invention I avoid subjecting the cracked bottoms to coking and instead carry on a cracking operation in which a liquid residue is produced while subjecting only the raw or original charging stock. Thus, in the practice of the invention, crude oil or residuum may be subjected to a polymerizing and distilling operation to reduce the oil to an ultimate pitch or coke residue and the evolved vapors may be delivered to a distilling or fractionating zone which may also receive cracked products from a cracking operation and the combined products are distilled to form a liquid residue such as is adapted for fuel oil.

In order to more fully disclose the invention, reference will now be had to the accompanying drawing which is a flow diagram of a particular embodiment of the invention.

In the system shown in the drawing fresh charging stock is drawn from a suitable source by a pump 10 and passed through a coil 11 positioned in a convection heating zone of a furnace 12. This charging stock is preferably a virgin stock, that is, a stock which has not been previously subjected to any material cracking operation and may, for instance, comprise a reduced crude, such as is obtained by straight distillation. The oil is heated in transit through the coil 11 and is then passed through a transfer line 13 into a coking chamber 14. The oil is preferably heated in the coil 11 to a temperature that will sustain coking or pitch-forming conditions in the chamber 14 and cracking may be carried on in the coil 11 to the extent desired. Steam may be introduced into the coking drum 14 to assist the coking or pitch-forming operation or a stream of a highly heated lighter charging stock may be directed into the coking drum to assist in maintaining therein conditions requisite for coking or pitch-forming.

The evolved vapors are withdrawn from the chamber 14 through a line 15 while the liquid

is retained therein so that the mass may be converted to a coke residue which may be removed through a manway 16 at the end of a run. A well 17 is indicated for suitable coke boring apparatus. The chamber 14 may be pluralized so that while one of the coke drums is being cleaned another may be utilized in the coke-forming operation. If desired, instead of running to a coke residue, the operation may be carried on so as to remove a pitch through a line 18 which is withdrawn as a liquid and solidifies upon cooling to form a product having a melting point.

The vapors evolved in the coke-forming or pitch-forming operation may be delivered by a line 15 to a distilling and fractionating tower 19. A condensate cut is removed from the tower by line 20 and pump 21 by which the condensate is charged through a line 22 to a heating coil 23 located in a radiant heating zone of the furnace 12. The oil is subjected to cracking in the coil 23 and is then delivered through a transfer line 24 to the distilling and fractionating tower 19. Thus, the cracked products from the cracking coil 23 and the vapors from the coking drum 14 are subjected to distillation and fractionation to form a cycle condensate for cracking, a vapor fraction which is taken off through the line 25 and a liquid residue withdrawn through a line 26. The vapor fraction is condensed in a condenser coil 27 and collected as a final light distillate in the receiving drum 28.

Although the coils 11 and 23 are illustrated as being disposed in the same furnace, it may be pointed out that these coils may, if desired, be in separately fired furnaces or heated in any suitable manner. If desired, in addition to the cracking coil, such as 23, a reaction chamber may be employed and the cracked products from the reaction chamber directed into the chamber 19.

A valve is indicated in the transfer line 13 so that if desired, the pressure carried in the coking still 14 may be lower than that obtaining in the coil 11, and similarly, a valve is shown in the transfer line 24 so that the cracking carried on in the cracking zone 23 may be under a higher pressure than the distilling and fractionating operation conducted in the chamber 19. The latter chamber may also be at a pressure lower than that in the coking still 14, a valve being indicated in the line 15 to accomplish such a reduction in pressure. Although the pressure conditions employed in the several parts of the apparatus may vary within comparatively wide limits, it may be

pointed out that an advantageous operation is to carry the heating coils 11 and 23 under several hundred pounds pressure while maintaining the coke drum 14 at a pressure of the order of 100 pounds and the distilling and fractionating chamber 19 at approximately the same pressure as the coking drum or at a lower pressure, for example, 50 pounds or lower.

In practicing the invention, an oil which may 10 preferably be a virgin stock, such as a straight-run reduced crude, is heated in the coil 11 sufficiently that when passed into the chamber 14 the desired pitch-forming or coke-forming conditions may be maintained therein with or without the 15 addition of steam or other heated oil as has been explained. In one method of operation contemplated a portion of the hot cracked products from the coil 23 and line 24 may be passed through a branch line 24a into the lower part of chamber 14. 20 The operation is preferably carried on with cracking in the coil 11 to such an extent as may be practiced without the formation of injurious coke deposits in the coil, and this virgin stock is thus reduced to a coke or pitch residue in the chamber 14. 25 The cycle stock which is cracked in the coil 23 is preferably subjected to a high degree of cracking and the cracked products, together with the vapors from the coke-forming or pitch-forming operation are subjected to distillation and 30 fractionation in the tower 19. The residue formed in the tower still 19 is not subjected to coking, but is drawn off as a liquid residue to form a liquid product adapted for fuel oil. The final gasoline or naphtha distillate is collected in the 35 receiver 28.

In case it is desired to charge to the system a crude petroleum or other oil containing a quantity of the lighter petroleum fractions it is advantageous to interpose a stripping or fractionating tower between the coking drum 14 and the distilling and fractionating tower 19. Thus the vapors from the coking drum 14, instead of passing directly to the tower 19, may be introduced into this intermediate tower into which also the 45 crude oil is introduced. The evolved vapors may then pass to the tower 19 and the resultant liquid residue may be drawn off, as by the pump 10, and charged to the heating coil 11.

Obviously many modifications and variations of the invention, as hereinbefore set forth, may be made without departing from the spirit and scope thereof, and therefore, only such limitations should be imposed as are indicated in the appended claims.

I claim:

1. A combined cracking and coking process comprising passing a crude residuum through a heating zone and continuously applying heat to 10 said crude residuum during its passage therethrough to raise it to a sufficiently high temperature to accomplish coking of the residual constituents thereof, passing said heated crude residuum from said heating zone directly to a coking zone 15 wherein vaporizable and residual constituents thereof are separated, retaining the separated residual constituents in the coking zone wherein they are reduced to coke by their retained heat, directing the vaporized constituents from said 20 coking zone into a separate distilling zone and then to a fractionating zone, passing a cycle condensate heavier than gasoline withdrawn from the fractionating zone through a heating zone and continuously applying heat to said cycle condensate during its passage therethrough to raise it to an elevated cracking temperature, passing all 25 of the products resulting from cracking the cycle condensate directly to said distilling zone, subjecting the vapors from the coking zone to fractionation and the products resulting from said 30 cracking to distillation and fractionation in the aforementioned distilling and fractionating zones to form said aforementioned cycle condensate, a final overhead light distillate and a fuel oil residue 35 which comprises the heaviest constituents formed in said distilling zone and separately withdrawing the fuel oil residue from the distilling zone without returning same to the process.

2. A process in accordance with claim 1 in 40 which a virgin stock is passed through the first mentioned heating zone.

3. A process in accordance with claim 1 in which the oil passing through each of the heating zones is maintained under superatmospheric 45 pressure during its passage therethrough.
